UNITED STATES PATENT OFFICE.

BROCKWAY DICKIE, OF ALBION, MICHIGAN, ASSIGNOR TO THE UNION STEEL PRODUCTS COMPANY, LTD., OF ALBION, MICHIGAN, A CORPORATION OF MICHIGAN.

CANNING-RACK.

1,379,000.

Specification of Letters Patent. Patented May 24, 1921.

Application filed May 8, 1920. Serial No. 379,928.

To all whom it may concern:

Be it known that I, BROCKWAY DICKIE, a citizen of the United States, residing at Albion, county of Calhoun, State of Michigan, have invented certain new and useful Improvements in Canning-Racks, of which the following is a specification.

This invention relates to improvements in canning racks.

10 My improved canning rack is particularly adapted for use in canning fruit by what is known as the "cold pack" process.

The main objects of this invention are to provide a canning rack which may be collapsed for storage or shipping and at the same time is quickly erected and when erected is effectively retained or supported in its erected position.

Further objects, and objects relating to 20 structural details will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing forming a 30 part of this specification, in which:

Figure I is a perspective view of a structure embodying the features of my invention shown in connection with a receptacle such as a boiler, parts of the boiler being broken 35 away.

Fig. II is an end elevation, a portion of the handle being broken away.

Fig. III is a plan view of the retaining frame and section on a line corresponding 40 to line 3—3 of Fig. II.

Fig. IV is a detail plan view of the base and section on a line corresponding to line 4—4 of Fig. II.

Fig. V is an enlarged detail section on a 45 line corresponding to line 5—5 of Fig. III.

Fig. VI is an edge view of the rack in its collapsed position.

Fig. VII is a side view of the rack in its erected position with parts broken away.

50 In the drawing, similar reference characters refer to similar parts throughout the several views, and the sectional views are taken looking in the direction of the little arrows at the ends of the section lines.

55 Referring to the drawing, my improved

canning rack comprises a base which in the structure illustrated consists of a border wire 1, longitudinal bars or rods 2, and cross rods 3. These are in practice formed of wire and are preferably joined by welding to each other at their crossing points or points of contact. I provide an upper or retaining frame comprising the border wire or member 4, a longitudinal rod 5, and cross rods 6. The cross rods are provided with 60 eyes 7 at their ends slidably embracing the border member so as to be adjusted laterally thereon, the cross rods being retained in their adjusted positions by engagement with the corrugations of the longitudinal rod. 65 This permits the adjustment for cans of different sizes, as pints, quarts or two quarts. These features of adjustment, however, form no part of my present invention and I have described the same in order that the structure illustrated might be fully understood.

The retaining frame is collapsibly supported by means of the links 8 formed of bail-shaped pieces of wire having eyes 9 engaging the base, the eyes being formed 70 in the ends of the arms of the links. The bight ends are looped over the retaining frame at 9 so that their cross portions 10 lie below the retaining frame. This arrangement permits the retaining frame being collapsed upon the base as shown in Fig. VI.

To hold the retaining frame in erected position, I provide locking members 11 and 12. These locking members have eyes 13 at 90 their upper ends engaging the cross portions 10 of the supporting links 8. The member 11 has a loop 14 at its lower end engaging one end of the base while the member 12 has a hook 15 at its lower end detachably engageable with the other end of the base.

As the pivot points or points of engagement for these locking members on the retaining frame and their points of engagement with the base are out of alignment with 95 the pivot points of the supporting links 8, they hold the retaining frame in erected position when the hook 15 is engaged but allow it to be collapsed when this hook is disengaged.

The handles 16 are pivotally mounted on the retaining frame and have hook like offsets 17 which may be engaged over the upper edge of a boiler or other receptacle 18.

My improved rack is very convenient to 110

use. It may be compactly collapsed for shipping or storage and when erected is securely retained in its erected position and is strong and durable.

Having thus described my invention what I claim as new and desire to secure by Letters Patent is:

1. In a canning rack, the combination of a base, a retaining frame comprising a border member and cross rods, bail-like supporting links for said retaining frame having eyes at the ends of their arms engaging said base, their bight ends being looped over said retaining frame border member with their cross portions within the ends of said base, locking members pivoted on said cross portions of said supporting links, one of said locking members being provided with a loop engaging one end of the base and the other with a hook detachably engageable with the other end whereby said retaining frame is held in its erected position when said hook is engaged.

2. In a canning rack, the combination of a base, a retaining frame comprising a border member and cross rods, supporting links for said retaining frame, locking members pivotally connected to said retaining frame, one of said locking members having a sliding engagement with one end of the base and the other with a hook detachably engageable with the other end, the pivotal points of said locking members on the support and their points of engagement with the base being out of alinement with the pivot points of the supporting links, so that when the hook is engaged the retaining frame is held in its erected position.

In witness whereof, I have hereunto set my hand and seal in the presence of two witnesses.

BROCKWAY DICKIE. [L. s.]
